UNITED STATES PATENT OFFICE.

CHARLES E. SMITH, OF BROOKLYN, NEW YORK, ASSIGNOR TO REMINGTON TYPE-WRITER COMPANY, OF ILION, NEW YORK, A CORPORATION OF NEW YORK.

TYPEWRITING MACHINE.

Original application filed April 6, 1922, Serial No. 550,045. Divided and this application filed January 11, 1923. Serial No. 611,922.

To all whom it may concern:

Be it known that I, CHARLES E. SMITH, citizen of the United States, and resident of the borough of Brooklyn, city of New York, in the county of Kings and State of New York, have invented certain new and useful Improvements in Typewriting Machines, of which the following is a specification.

My invention relates to typewriting and like machines and more particularly to so-called portable machines intended to be inclosed and transported in a carrying case.

The main object of my invention, generally stated, is to insure a proper conditioning of a portable machine for transportation.

In such machines it is highly desirable to release the carriage from restraint of its escapement or feed device before the machine is inclosed in its carrying case, and to maintain the carriage thus released until the machine is about to be used, when it is desirable to re-establish the connections by which the carriage is restrained by its feed mechanism. This is in order that the weight of or jolts from the carriage, while the machine is being transported or carried in its case, may not be exerted on the carriage feed devices and which, if so exerted, might result in injuring or breaking said devices.

This is one of the factors that enters into consideration in conditioning the machine for transportation, and which is taken care of by my invention. Another factor is the necessity of placing the carriage in a centered position in its line of travel in order that the close fitting cover of the case may be closed without interference from the machine and to hold or lock the carriage against traveling movement from such centered position when it is released from the restraint of its feed devices.

By my present invention I provide simple and highly effective improved means for accomplishing these results, such means being necessarily actuated to free the carriage from restraint of its escapement devices before the case can be closed and necessarily actuated to re-establish such restraint of the carriage by its escapement devices before the machine can be actuated. I also provide means by which the centering lock is necessarily rendered effective and ineffective.

To the above and other ends which will hereinafter appear my invention consists

in the features of construction, arrangements of parts and combinations of devices, set forth in the following description and particularly pointed out in the appended claims.

This case is a division of my application, Serial No. 550,045 filed April 26, 1922.

In the accompanying drawings, wherein like reference characters designate corresponding parts in the different views,

Figure 1 is a detail fragmentary vertical fore-and-aft sectional view showing the rear portion of a machine contained within its carrying case and properly conditioned for transportation; the section being taken on the line 1—1 in Fig. 3 and looking in the direction of the arrows at said line.

Figure 2 is a like view of the same with the cover of the case removed and the machine shown in condition for use.

Figure 3 is a fragmentary vertical transverse sectional view of the case showing the machine contained therein and as viewed from the rear.

Figure 4 is a detail horizontal sectional view of the carriage and its support, the section being taken on the line 4—4 of Fig. 2 and looking in the direction of the arrows at said line.

Figure 5 is a detail perspective view of one of the carriage locking members, shown detached.

Figure 6 is an enlarged detail vertical sectional view showing the finger wheel and some of the associated parts, the section being taken on the line 6—6 of Fig. 2 and looking in the direction of the arrows at said line.

Figure 7 is a detail perspective view of the carrying case inclosing the machine.

I have shown my invention in the present instance embodied in a Remington portable machine, many of the features of which are shown in the following patents and pending applications:

A. W. Smith, Pt. No. 1,342,513, dated June 8, 1920; J. B. Holden, Pt. No. 1,386,256, dated Aug. 2, 1921; J. B. Holden, App. Sr. No. 469,458, filed May 14, 1921; J. B. Holden, App. Sr. No. 541,355, filed Mch. 6, 1922; J. B. Holden App. Sr. No. 547,128, filed Mch. 27, 1922; G. A. Seib, App. Sr. No. 529,415, filed Jan. 16, 1922. It should be understood, however, that the invention is

not restricted to embodiment in a machine of this style.

From certain aspects of my invention it is in the nature of improvements on the construction disclosed in the above mentioned Holden application, Sr. No. 547,128.

The Remington portable machine is provided with a carrying case, the cover of which can be closed only when collapsible parts of the machine are moved to compact relation with the remainder of the machine and when the carriage is properly centered on its support, as pointed out in the above mentioned application, Sr. No. 547,128. In said application, means also are disclosed for locking the carriage in a centrally disposed position on the machine in order that the cover of the case may be closed, and the feed rack is moved to releasing position by hand and is maintained in such position by a separately actuated collapsible part of the machine, such as the finger wheel of the platen. By my present invention, I provide improved means for locking the carriage in its centered position which are automatically actuated or rendered effective by a compactible part of the machine and which must necessarily be actuated before the case can be closed. I also provide automatically operating means for releasing the carriage from the restraint of its feed devices by the same operation of said compactible part.

In the accompanying drawings I have shown only so much of the Remington portable machine as is necessary to arrive at an understanding of my invention in its embodiment therein.

The outer sheet metal frame 1 of the machine contains an inner sheet metal frame 2 by which various working parts of the machine are supported. Among such parts is a carriage supporting case shift frame, such as is illustrated in the above mentioned patent, No. 1,386,256. This case shift frame comprises a carriage support 3 pivoted at 4 on upright arms 5 secured to a rock shaft 6 pivoted at its ends, as at 7, to the inner frame, so that the carriage support may receive a case shifting movement fore-and-aft of the machine.

The carriage support has two grooved guide-rails or plates 8 and 9 secured thereto. These guide-rails contain crossed bearing rollers 10 that are received in ways in the rails 8 and 9 and in companion grooved rails or ways 11 and 12 respectively formed in the bent edge portions of the main base plate 13 of the carriage. This plate has fixed thereto carriage end plates 14 and 15, and such end plates support a platen 16. The case shiftable but non-foldable carriage is thus mounted to travel from side to side of the machine, and supports the platen at all times in printing position where it is adapted to receive the impact of downwardly

and rearwardly striking type bars (not shown) on the upper side thereof.

The step-by-step feed movement of the carriage is controlled by escapement mechanism comprising, in the present instance, feed dogs 17 and 18 carried by a key controlled dog rocker and engaging teeth 19 of a feed rack 19. The feed rack is carried by a sheet metal plate 20 which has upwardly and forwardly bent arms 21 and 22. The arm 21 is bent at its free end portion to form a pivot bearing 23 that receives a pivot rod 24; such rod being supported in bearings 25 of a bracket which is secured to the base plate 13 of the carriage. The arm 22 is secured by a screw 26 to a block 27, apertured to receive a pivot rod 28; such rod being supported in bearings 29 of a bracket plate 30, secured by screws 31 to the base plate 13 of the carriage. Coiled springs 32 surround the pivots 24 and 28 and each bears at one end 33 on the associated bracket plate, and at its other end 34 against the plate 20 and normally holds the feed rack in its effective or engaging position, as shown in Fig. 2. The rack is limited in its movement in this direction by the arms 21 and 22 bearing against the rear ends of two screw stops 35 and 36 respectively, threaded into tapped openings in the bent edge portion 12 of the carriage base plate. Fixed at 37 to the left-hand end of the plate 20, is an upwardly and rearwardly extending feed rack release arm 38, which terminates in a finger piece 39. A forward movement of the finger piece 39, from the position shown in Fig. 2, to that indicated in Fig. 1, is effective to disengage the feed rack from the normally engaged feed dog 18, and thus free the carriage from the restraint of its escapement mechanism. The forward movement of the arm 38 to releasing position is limited by a laterally projecting lug 40 (see Figs. 2 and 3), that coacts with a stop 41 formed on the rear edge of the end plate 15, as shown in Figs. 1 and 2.

One of the collapsing parts of the Remington portable machine is the finger wheel 42, which is movable from the dotted line position of use, to the full line compact position shown in Fig. 3, as pointed out in the hereinbefore mentioned application, Sr. No. 547,128. Referring particularly to Fig. 6, it will be seen that the finger wheel 42 is fixed by a screw 43 to a spindle or platen shaft 44 which is movable longitudinally in the right-hand platen head 45; a spline 46 on the latter extending into a spline groove 47 in the spindle. Screws 45 secure the platen head 45 to the core of the platen 16. A pin 48 on the spindle coacts with the spline 46 to limit the outward movement of the spindle and finger wheel, as shown. A flanged bearing sleeve 49 surrounds the spindle 44 and is supported in an opening in the right-

hand end plate 14 of the carriage. The bearing sleeve 49 is held in place in the opening in the end plate 14 by a washer 50 riveted at 50^a to the sleeve. The left-hand 5 end portion of the platen spindle is supported in a corresponding flanged bearing sleeve 51 fixed in an opening in the left-hand end plate 15 like the sleeve 49. In this manner the platen is mounted in the platen carrier 10 or carriage, and the finger wheel 42 is connected to turn with the platen but may be moved longitudinally thereof from the full to the dotted line position in Fig. 3, or vice versa.

15 The sleeve 51 has a laterally extending slot 52 cut therein to a point where it crosses the bore 53 in the sleeve. A sheet metal member or finger 54 is received in the slot 52, and has a movement therein transversely of 20 the spindle 44 from the position shown in Fig. 1, to that indicated in Fig. 2, or vice versa. When the finger wheel is in the expanded or dotted line position shown in Fig. 3, the left-hand cone-like end of the spindle, indicated at 44^a in said figure and in Fig. 6, is positioned to the right of the lateral slot 52. The pointed end portion 44^a is in the nature of a cam which coacts with a rounded edge 54^a of the member 54 and shifts it 25 from the Fig. 2 to the Fig. 1 position when the finger wheel 42 is moved to the compact or full line position shown in Fig. 3. During the last portion of the movement of the finger wheel to this position the cylindrical 30 portion of the spindle 44 will be brought into co-operation with the finger 54, and prevents the latter from returning to the Fig. 2 position so long as the finger wheel remains in the pushed in, or compact position.

35 In the present instance the finger 54 constitutes part of a sheet metal controlling member, designated as a whole by the reference numeral 55. As will be seen upon reference to Fig. 4, this member is pivoted on the shank of an interiorly threaded, headed screw 56, screwed onto a shoulder screw 57 that passes through an opening in the end plate 15. A spring 59 is wound around a 40 pin 60 projecting from the outer face of the end plate 15, and it is anchored at one end, as at 61, whereas the free end 61^a of the spring bears against a projection 58^a which if desired may be in the nature of a finger piece on the member 55. This projection 58^a is bent inwardly or to the right back of the carriage release arm 38, as in the Remington portable machine, so that a forward movement of the arm 58 carries with it the arm 38, thus effecting a release of the carriage from restraint of its feed devices. The force of the spring 59 is exerted to return the controlling member 55 to the Fig. 2 position when it is freed from restraint of the spindle 44 by moving the finger wheel 42 to the 45 dotted line position in Fig. 3. The free end of the finger 54 coacting with the bottom wall of the slot 52 limits the movement of the member 55 in this direction.

50 The controlling member 55 also carries a locking finger or device 62 which constitutes one member of a lock for locking the carriage in a centralized position on its support 3, as shown in Figs. 1 and 3. This finger 62 registers with a slot 62^a in the base plate 13 of the carriage and is adapted, at any point in the travel of the carriage, to be moved through said slot from the ineffective position shown in Fig. 2, to the effective position shown in Fig. 1. In this last mentioned position, the lower edge portion of the locking finger 62 extends into co-operative relation with the companion locking member carried by the carriage support 3. If at this time the carriage be moved in either direction of its travel from an off-centered position, the locking members will coact when the carriage reaches the centralized position on its support, and will automatically lock the carriage against 55 movement from such position in either direction. The companion locking member on the support 3 is shown detached in Fig. 5, and in the present instance comprises a strip of spring metal 63 fastened by a headed screw 64 to the under side of the support 3; the stem of the screw passing through an opening 65 in the locking member. From one edge of the strip 63 is bent an upwardly extending detent 66 having a 60 slot or recess 67 therein. The upper edge of the detent is beveled outwardly and downwardly in opposite directions from the side walls of the recess 67, as indicated at 68. The detent 66 projects up through a slot 69 in the left-hand end portion of the support 3, so that the beveled edge portions 68 of the detent extend above the upper side of the member 3, and are normally maintained in such position by the inherent resiliency, or spring pressure, of the strip 63. The construction is such that when the locking finger 62 is in the effective position, and the carriage is moved in either direction towards a centralized position, it will bring the lower edge of the finger 62 against one or the other of the two bevels 68 and flex the detent downward. When the centralized position, shown in Fig. 3, is reached the recess 67 will register with the finger 62 and 65 the detent 66 will spring upward so as to engage the locking finger on both sides by the side walls of the recess 67, and thus prevent a movement of the carriage in both directions. When, however, the member 55 is moved to the Fig. 2 position, the finger 62 will be withdrawn from the recess 67 to free said finger from the detent, and the path of movement of the finger with the carriage is clear of the detent. The car- 70 75 80 85 90 95 100 105 110 115 120 125 130

riage is therefore free to be moved in either direction of its travel, so far as the centralized locking means are concerned.

The carrying case of the Remington portable machine comprises a base-board 70, to which the machine is attached by means such as are disclosed in the above mentioned application Sr. No. 469,458, but which need not be described herein. A cover 71 with its fixed rear wall 72, side walls 73, front wall 74 and top wall 75 is detachable from the base-board, and may be swung downwardly and forwardly into closed position around the machine on the pivot projections 76 on the base-board. By such movement the cover brings the rubber blocks or contacts 77 thereon into engagement with the carriage, as disclosed in the above mentioned application Sr. No. 541,355.

From an inspection of Fig. 3 it will be understood that when the finger wheel 42 is in the expanded or dotted line position, the lateral or widthwise dimension of the machine is increased and the cover cannot be closed since the wheel 42 stands in the path of the cover and prevents it from closing. At this time the member 55 is held by its spring 59 in the position shown in Fig. 2; with the locking member 62 withdrawn to ineffective position and the feed rack 19 normally engaging the dog 18. This is the condition of the machine for use, and from what has been said above it will be understood that this condition of the machine must be changed before it can be inclosed within its carrying case. One such change of condition is to move the finger wheel 42 to the full line position in Fig. 3. This movement of the wheel contracts the lateral dimension of the machine and is effective, through the movement of the cam 44^a, to shift the controlling member 55 and project the spindle 44 in the path of the finger 54, thereby holding the member 55

against return movement from the Fig. 1 position, to which it has been shifted by the cam 44^a. The described shifting of the member 55 to the Fig. 1 position results in moving the locking member 62 to effective position and also in disengaging the feed rack 19 from the feed dog 18, thus freeing the carriage from restraint of its feed mechanism.

So far as the construction under consideration is concerned, the machine is now in condition to be inclosed within its case, and the cover may be closed without further obstruction therefrom. The carriage at this time being held by its lock in the centered position cannot, of course, move from said position either to right or left notwithstanding the fact that it is no longer under control of its escapement. Any shocks or jolts to which the case and inclosed machine may be subjected will be resisted by the carriage

lock, and will not be imparted to the escapement mechanism. The parts will remain in this condition until the machine is again to be placed in condition for use. To condition the machine for use, so far as the parts described are concerned, the finger wheel 42 is moved out of compact relationship to the dotted line position in Fig. 3, thereby permitting the controlling member 55 to move from the Fig. 1 to the Fig. 2 position, and effect a release of the carriage lock by withdrawing the locking member 62 to ineffective position and also enable the feed rack to reengage the feed dog 18, restoring the carriage to the control and restraint of its feed mechanism. The machine is now ready for use.

The force of the spring 59, acting through the finger 54 on the cam 44^a, is sufficient to prevent an accidental displacement of the finger wheel 42 from the expanded to the compact position while the machine is in use, and yet enable the finger wheel to be shifted to such compact position when sufficient force is exerted thereon to overcome the resistance of the spring 59.

In the Remington portable machine the carriage receives a rearward bodily case shifting movement, and when inadvertently left locked in such position prevents the cover from closing. In order that there may be no danger in such circumstances of bending or injuring the parts should an attempt be made to force the cover closed, I prefer to employ the means disclosed in my application, Sr. No. 538,267, filed Feb. 21, 1922, for automatically releasing the case shift lock before the cover can be closed on the machine. With the use of such means the carriage cannot be maintained in the rearmost case position when the machine is otherwise conditioned for transportation, and no injury to the parts can result when closing the cover.

From the foregoing description it will be seen that I have provided a collapsible part of the machine, such as the finger wheel 42, movable relatively to the platen and by which the lateral dimension of the machine may be reduced together with means whereby when said part is moved to compact position it positively moves a controlling member 55 to render and hold the center lock effective and release the carriage from restraint of its escapement and thus condition or aid in conditioning the machine for portability. From a broad aspect of the invention various devices may be thus controlled by said collapsible or compactible part to attain the ends stated.

I have elected to prosecute herein generic claims which cover certain features disclosed in my hereinbefore mentioned parent application Sr. No. 550,045, as well as the form of construction shown and described herein.

The claims of said parent application are restricted to features of construction not disclosed in this case.

By my invention I have provided simple means that not only automatically effect the release of the carriage from restraint of its escapement before the machine can be inclosed in its case, but also automatically render the center lock effective and compel the proper centering and locking of the carriage by the members 62 and 66 before such a result can be obtained. I therefore insure a proper conditioning of the machine before it can be inclosed in its case for transportation, and prevent injury to the parts of the machine that might result except for such proper conditioning.

Various changes may be made without departing from the scope of my invention as defined in the accompanying claims and various parts may be used without others.

What I claim as new and desire to secure by Letters Patent, is:—

1. In a typewriting or like machine, the combination of a carriage, a platen carried thereby, feed mechanism for said carriage, a finger piece for turning said platen, said finger piece being shiftable to and from compact position and adapted to remain indefinitely in either of said positions, and means controlled by said finger piece for releasing the carriage from the restraint of its feed mechanism.

2. In a typewriting or like machine, the combination of a carriage, a platen carried thereby, feed mechanism for said carriage, a finger piece for turning said platen, said finger piece being shiftable to and from compact position and adapted to remain indefinitely in either of said positions, and means controlled by said finger piece for releasing the carriage from the restraint of its feed mechanism when the finger piece is shifted to compact position and for restoring the carriage to restraint of its feed mechanism when the finger piece is shifted from compact position.

3. In a typewriting or like machine, the combination of a carriage, a platen carried thereby, feed mechanism for said carriage, a center lock for locking the carriage centered in its line of travel, a finger piece for turning the platen, said finger piece being shiftable to and from compact position, and means controlled by said finger piece for releasing the carriage from restraint of its feed mechanism and for rendering said center lock effective.

4. In a typewriting or like machine, the combination of a carriage, a platen carried thereby, feed mechanism for said carriage, a center lock for locking the carriage centered in its line of travel, a finger piece for turning the platen, said finger piece being shiftable to and from compact posi-

tion, and means controlled by said finger piece for releasing the carriage from restraint of its feed mechanism and for rendering said center lock effective when the finger piece is shifted to compact position 70 and for restoring the carriage to restraint of its feed mechanism and rendering the center lock ineffective when the finger piece is shifted from compact position.

5. In a typewriting or like machine, the combination of a carriage, feed mechanism therefor, a center lock for locking the carriage in a centered position in its line of travel, a part of the machine movable to and from compact position, and means controlled by the movement of said part to compact position for releasing the carriage from restraint of its feed mechanism and for rendering said center lock effective.

6. In a typewriting or like machine, the combination of a carriage, feed mechanism therefor, a center lock for locking the carriage in a centered position in its line of travel, a part of the machine movable to and from compact position, and means controlled by the movement of said part to compact position for releasing the carriage from restraint of its feed mechanism and for rendering said center lock effective and for restoring the carriage to restraint of 95 its feed mechanism and rendering said center lock ineffective by the movement of said compactible part from compact position.

7. In a typewriting or like machine, the combination of a carriage, feed mechanism therefor, a hand actuated release key operable at will to release the carriage from the restraint of its feed mechanism, a center lock for locking the carriage in a centered position in its line of travel comprising a member effective to move said carriage release key to releasing position, a part of the machine shiftable to and from compact position and adapted to remain indefinitely in either of said positions, and means controlled by the movement of said compactible part to compact position for moving said member of the center lock and thereby render the center lock effective and release the carriage from restraint of its feed mechanism.

8. In a typewriting or like machine, the combination of a carriage, a platen carried thereby, feed mechanism for said carriage, a hand actuated release key operable at will to release the carriage from the restraint of its feed mechanism, a center lock for locking the carriage in a centered position in its line of travel comprising a member effective to move said carriage release key to releasing position, a finger piece for turning the platen and which is shiftable to and from compact position and adapted to remain indefinitely in either of said positions, and means controlled by the move-

ment of said finger piece to compact position for moving said member of the center lock and thereby render the center lock effective and also release the carriage from restraint of its feed mechanism.

9. The combination with a typewriting or like machine having a carriage, feed mechanism therefor, a platen and a finger piece for turning the platen, said finger piece being movable from an expanded to a compact position to reduce a dimension of the machine, of a carrying case for said machine which is prevented from being closed by said finger piece when the latter is in its expanded position, and means controlled by the movement of said finger piece to contracted position for releasing the carriage from restraint of its feed mechanism.

10. In a typewriting or like machine, the combination of a carriage, feed mechanism therefor, a platen carried by the carriage, a finger piece for turning the platen, a spindle on which said finger piece is mounted and which is movable longitudinally of the platen, a cam on said spindle, and means controlled by said cam for freeing the carriage from restraint of its feed mechanism.

11. In a typewriting or like machine, the combination of a carriage, feed mechanism therefor, a center lock for locking the carriage centered in its line of travel, a platen carried by the carriage, a finger piece for turning the platen, a spindle on which said finger piece is mounted and which is movable longitudinally of the platen to enable the finger piece to be moved to and from compact position, a cam on said spindle, and means controlled by said cam for freeing the carriage from restraint of its feed mechanism and for rendering said center lock effective.

12. The combination with a typewriting or like machine having a carriage, feed mechanism therefor, a platen, and a finger piece movable from an expanded position to a compact position to reduce a dimension of the machine, of a carrying case for said machine which is prevented from being closed by said finger piece when the latter is in its expanded position, means for locking the carriage in a centralized position including a locking member shiftable to and from effective position, means whereby said locking member is moved to effective position when the finger piece is moved to compact position, and means for releasing the carriage from the restraint of its feed mechanism by said last mentioned movement of said finger piece.

13. In a typewriting or like machine, the combination of a carriage, feed mechanism therefor, a platen carried thereby, a finger piece for turning the platen, a spindle on which said finger piece is mounted and which is movable longitudinally of the

platen to enable the finger piece to move to and from compact position, a cam on said spindle, a member movable on the carriage and co-operative with said cam to be moved thereby, a lock for the carriage, one part of which is moved to and from effective position by said member, and means controlled by said member for freeing the carriage from restraint of its feed mechanism.

14. In a typewriting or like machine, the combination of a carriage, feed mechanism therefor, a platen carried by the carriage, a finger piece for turning the platen, said finger piece being shiftable to and from compact position, a center lock for locking the carriage in centered position in its line of travel, and means controlled by a mere actuation of said finger piece for freeing the carriage from restraint of its feed mechanism and for rendering said center lock effective.

15. A collapsible typewriting or like machine having a carriage, feed mechanism therefor, a center lock for locking the carriage in a centered position in its line of travel, and automatically operating means controlled by a compactible part of the machine for freeing the carriage from restraint of its feed mechanism and for rendering said center lock effective.

16. In a typewriting or like machine, the combination of a carriage, a platen carried thereby, a finger piece for turning the platen and which is shiftable to and from compact position, a carriage lock comprising a controlling member the position of which determines the effectiveness or ineffectiveness of the lock, and means controlled by the movement of said finger piece for moving said controlling member.

17. In a typewriting or like machine, the combination of a platen, a finger wheel for the platen shiftable to and from compact position and adapted to remain indefinitely in either of said positions but connected at all times to turn with the platen, and a controlling member to aid in conditioning the machine for portability and the movement of which in one direction is controlled by said shifting of the finger wheel to compact position, the movement of the controlling member in the opposite direction being controlled by the shifting of the finger wheel from compact position.

18. In a typewriting or like machine, the combination of a carriage, a finger wheel therefor movable to and from compact position, and a carriage centering lock that is automatically rendered effective by the movement of the finger wheel to compact position.

19. The combination with a typewriting or like machine having a part movable from an expanded to a compact position to reduce a dimension of the machine, of a carrying

- case for said machine which is prevented from being closed by said compactible part when the latter is in its expanded position, a carriage lock for holding the carriage 5 against movement in both directions from a centered position in its line of travel, and means controlled by the movement of said part to compact position for shifting a member of said lock to effective position where it 10 will automatically coat with another member of said lock by the travel of the carriage to the centered position from either the right or the left.
20. The combination with a typewriting or like machine having a platen, and a finger wheel therefor movable from an expanded to a compact position to reduce a dimension of the machine, of a carrying case for said machine which is prevented from being 15 closed by said finger wheel when the latter is in its expanded position, means movable into and out of effective position and operative to further aid in conditioning the machine for portability, and means whereby 20 said last mentioned means are moved to one of said positions by the movement of the finger wheel to compact position.
21. In a typewriting or like machine, the combination of a platen, a finger wheel 30 therefor shiftable to and from compact position, a carriage centering lock comprising a member shiftable into and out of effective position, and means whereby the movement of said finger wheel to compact position 35 moves said member to effective position, and a movement of the finger wheel from compact position enables said member to move to ineffective position.
22. The combination with a typewriting or like machine having a part movable from an expanded to a compact position to reduce a dimension of the machine, of a carrying case for said machine which is prevented from being closed by said compactible part when the latter is in its expanded position, a carriage locking member, and means by which said locking member is positively moved to and held in effective position by the movement of said compactible 45 part to compact position and where it will automatically coat with another member of said lock to lock the carriage centered when moved to the centered position from either the right or the left of said centered position.
23. In a typewriting or like machine, the combination of a carriage, a platen carried thereby, a finger piece for turning the platen, a spindle on which said finger piece is mounted and which is movable longitudinally of the platen to enable the finger piece to move to and from compact position, a cam on said spindle, a member movable on the carriage and co-operative with said cam 60 to be moved thereby, and means controlled by said member for conditioning the machine for portability.
24. The combination with a typewriting or like machine having a carriage, a platen, and a finger wheel movable from an expanded position to a compact position to reduce a dimension of the machine, of a carrying case for said machine which is prevented from being closed by said finger wheel when the latter is in its expanded position, means 70 for locking the carriage in a centralized position and including a locking member shiftable to and from effective position, and means whereby said locking member is moved to effective position when the finger 75 wheel is moved to compact position.
25. In a typewriting or like machine, the combination of a carriage, a platen carried thereby, a finger wheel for the platen, a spindle on which said finger wheel is mounted and which is movable longitudinally of the platen to enable the finger wheel to move to and from compact position, a cam on said spindle, a member movable on the carriage and co-operative with said cam to 80 be moved thereby, and a lock for the carriage, one part of which is moved to and from effective position by said member.
26. In a typewriting or like machine, the combination of a carriage, a platen, a finger piece for turning the platen and which is shiftable to and from compact position, a member pivoted on an end plate of the carriage and the movement of which is controlled wholly by the movement of the finger 85 wheel to and from compact position, and carriage releasing means controlled by said pivoted member.
27. In a typewriting or like machine, the combination of a carriage, a platen, a finger wheel therefor shiftable to and from compact position, a member pivoted on an end plate of the carriage and the movement of which is controlled wholly by the movement of the finger wheel to and from compact 90 position, and a carriage lock controlled by said member.
28. In a typewriting or like machine, the combination of a part movable from an expanded to a compact position to reduce a dimension of the machine, a carriage lock for holding the carriage against movement in both directions from a centered position in its line of travel, and means controlled by the movement of said part to compact position for shifting a member of said lock to effective position where it will automatically coat with another member of said lock by the travel of the carriage to the centered position from either right or left.
29. The combination with a typewriting or like machine having a part movable from an expanded to a compact position to reduce a dimension of the machine and also having a center lock for holding the carriage 100

against movement in both directions from a centralized position in its line of travel, of a carrying case for said machine which is prevented from being closed by said compactible part when the latter is in its expanded position, and means controlled by said compactible part, for rendering said center lock effective and for freeing the carriage from restraint of its escapement mech-

anism before said carrying case can be closed. 10
Signed at the borough of Manhattan, city of New York, in the county of New York and State of New York, this 8th day of January, A. D. 1923.
